UNITED STATES PATENT OFFICE.

SAMUEL L. KISTLER, OF LOS ANGELES, CALIFORNIA.

RECTAL INSTRUMENT.

SPECIFICATION forming part of Letters Patent No. 694,971, dated March 11, 1902.

Application filed July 8, 1901. Serial No. 67,565. (No model.)

To all whom it may concern:

Be it known that I, SAMUEL L. KISTLER, a citizen of the United States, residing at Los Angeles, in the county of Los Angeles, State 5 of California, have invented new and useful Improvements in Rectal Instruments, of which the following is a specification.

My improvement relates to instruments for treating rectal diseases, such as piles, fissures, &c.; and the object thereof is to provide a simple instrument by means of which constant application of unguents may be made to the affected parts and which may be retained in place without external aid. I accomplish these objects by the rectal instrument described herein and illustrated in the accompanying drawings, in which—

Figure 1 is a side elevation of my instrument. Fig. 2 is a central longitudinal section thereof.

In the drawings, A is an imperforate reservoir having a screw-threaded opening in its base, preferably pear-shaped in form, adapted to hold a considerable quantity of unguent, 25 which is screwed upon the hollow stem B, having its opposite end closed and provided with a base-piece B', adapted to fit against the body and prevent the instrument from passing into the body. In the stem, intermediate the base and the reservoir, are a number of slots C, through which the unguent passes to the parts to be treated.

In the operation of my device the reservoir and stem are filled with unguent and the stem 35 is screwed into the reservoir and the reservoir is inserted into the rectal canal and passes up beyond the inner sphincter muscle, which leaves the stem in contact with the sphincter muscles and the parts therebetween. It is principally these parts which 40 become affected with hemorrhoids, fissures,

and other troubles and which require the application of unguents to cure the same. By my instrument the unguent is directly applied to the parts affected as they are in contact 45 therewith through the slots in the stem. As the unguent in the stem is absorbed by the surrounding tissue a fresh supply is fed thereinto from the reservoir, thereby making a continuous treatment of the affected parts. 50

Having described my invention, what I claim as new, and desire to secure by Letters Patent, is—

1. In an instrument for applying unguents to the rectum, the combination of an imperforate hollow pear-shaped reservoir provided with an opening in its base for the introduction thereinto of an unguent, of a hollow stem of uniform diameter opening into said reservoir and removably connected to the base of 60 the reservoir and being of less diameter than the largest diameter of the reservoir, said stem being closed at its other end and being provided with a base-piece affixed to the closed end of the stem and perforations intermediate the base-piece and reservoir. 65

2. In a rectal instrument the combination with an imperforate hollow reservoir provided with a screw-threaded opening at its base, with a hollow perforate stem of uniform diameter opening into the reservoir and being of less diameter than the largest diameter of the reservoir and closed at its other end; said stem being provided at its closed end with a base-piece. 70

In witness that I claim the foregoing I have hereunto subscribed my name this 3d day of July, 1901.

S. L. KISTLER.
